UNITED STATES PATENT OFFICE.

GEORGE A. HUGHES AND TREVOR M. CAVEN, OF CHICAGO, ILLINOIS, ASSIGNORS TO
HUGHES ELECTRIC HEATING COMPANY, OF CHICAGO, ILLINOIS, A CORPORATION
OF ILLINOIS.

ELECTRICAL HEATING DEVICE.

1,049,488.

Specification of Letters Patent.

Patented Jan. 7, 1913.

Application filed June 11, 1910. Serial No. 568,298.

To all whom it may concern:

Be it known that we, GEORGE A. HUGHES and TREVOR M. CAVEN, residents of Chicago, in the county of Cook and State of Illinois, have invented certain new and useful Improvements in Electrical Heating Devices, of which the following is a full, clear, and precise specification.

Our invention relates to electrical heating devices, and concerns particularly an improved form of heating unit, the arrangement of such unit in a stove frame, and the electrical connections and control for the unit.

Among the salient objects of our invention are to provide a heating unit which has a maximum heating efficiency with a minimum of volume and surface; to construct the heating wire supporting block of the unit of material which is highly conductive to heat, so that this supporting block will quickly take on the heat generated by the windings to thereby relieve the windings of intense heat which might cause burning thereof, and to add its heat radiating surface to that of the windings; to provide a supporting base or block for the unit, which base or block is constructed of heat insulating material to thereby confine the radiation of heat from the unit block and windings to objects set over the unit to be heated; to provide a plurality of resistance sections for the unit and improved electrical connections whereby said resistance sections can be put into circuit in various combinations to produce low degrees of heat, intermediate degrees of heat, and high degrees of heat; to provide improved terminal members on the unit for the resistance sections and improved companion terminal members on the supporting base, and to adapt the terminals for detachable engagement with each other so that the unit can be applied or removed from the stove frame without the necessity of disconnecting any wires or conductors, and so that the installation or removal of a unit will be automatically accompanied by its connection with or disconnection from the current supply circuit; and in general to provide for improved construction and operation of devices of the character referred to.

The nature of our invention is clearly brought out in the following specification

and shown on the accompanying drawings, 55, in which drawings

Figure 1 is a perspective view of a stove, showing a heating unit in place thereon, Fig. 2 is plan view of a heating unit, together with circuit controlling arrangement 60, therefor, and showing the circuit controlling switch mechanism in one position, Figs. 2^a and 2^b show the switch mechanism in different positions, Fig. 3 shows the heating unit in side elevation and the inclosing 65 block and part of the stove top in section on line 3—3, Fig. 1, Fig. 4 is a bottom view of the heating unit, Fig. 5 is a plan view of the supporting base, Fig. 6 is an end view of a block partly in section, and showing a 70 modified construction, and Figs. 7 and 8 are end views of part of a unit showing other modified constructions.

Referring to Figs. 2 and 3, the block 1 of the heating unit is in the form of a rectangular plate having a central longitudinal ridge 2, and at each side of this ridge is a plurality of narrower ridges 3 forming substantially semi-cylindrical grooves 4 which accommodate resistance sections 5 in 75 the form of wire coils. The ends of the ridges terminate a distance short of the ends of the block to leave flat transverse sections 6 and 7 for accommodating the various 80 terminal screws 8, under whose heads the ends 85 of the resistance coils are secured in electrical contact, the heads of these screws being preferably below the upper plane of the ridges. Five such resistance sections are shown at each side of the central ridge 2, although any number of such sections could, 90 course, be provided.

In Figs. 2 and 4 the circuit connections between the resistance section ends are illustrated. Referring to the resistance sections 95 as a, b, c, d, e, f, g, h, i and j, the sections at one end are connected as follows: a and e, d and f, g and i, and h and j; and at the other end the sections are connected as follows: a and c, b and d, e and g, and f and h, the 100 various connecting members 9 being either in the form of wires or of bands, whose ends are electrically connected with the terminal screws 8 by nuts 10 on the under side of the block, as shown in Fig. 4. A conductor plate 105 11 is held against the bottom of the block and in electrical contact with the terminal screw of resistance section a by means of a nut 10,

which plate extends inwardly and is provided with a downwardly extending contact pin 12. A similar conductor plate 13 is secured to the terminal screw of resistance section *b* and has the downwardly extending contact pin 14. Two conductor plates 15 and 16 are connected together at one end and support a downwardly extending contact pin 17, the opposite ends of the plates being secured to the terminal screws of the resistance sections *i* and *j*, these plates forming a direct connection between the outer ends of these sections. The contact pins 12, 14 and 17 are adapted to engage with terminal jaws provided on the supporting base 18. Referring to Figs. 1, 3 and 5, this supporting base is of cylindrical outside contour and has a square central pocket 19 of substantially the same size as the heating unit block, so that the heating unit block can be readily applied therein, as shown particularly in Figs. 1 and 3. At one corner of the pocket 19 terminal plates 20 and 21 are secured against the bottom of the pocket by means of screws 22 and 23 extending through the floor 24 of the supporting base and threading into the plates. The plate 20 mounts a spring jaw 24, and the plate 21 mounts a spring jaw 25, these spring jaws extending upwardly and in position to receive and to clamp the contact pins 12 and 14 of the heating unit. At the opposite corner of the supporting base a terminal plate 26 is held against the bottom of the pocket by a screw 27 passing through the floor 24 and threading into the plate, the end of the plate supporting a spring jaw 29 in position to receive the contact pin 17 on the heating unit. With this arrangement, when a unit is dropped into the supporting base, its contact terminals will engage with the terminal jaws, and electrical connection is thus automatically established, and upon the removal of the heating unit from the base the contact pins are withdrawn from the terminal jaws and the electrical connections automatically broken.

As shown in Figs. 1 and 3, the top 30 of the stove *S* is deflected downwardly to form the cylindrical pocket 31 for receiving the supporting base. The supporting block 1 of the heating unit is preferably constructed of material such as quartz composition which is highly conductive to heat, so that as the resistance sections are heated the material in the supporting block will take on heat and thus relieve the resistance sections of intense heat which might result in burning out of the sections. The supporting block will distribute the heat and will add to the total radiating surface of the unit. The supporting base 18 for the heating unit is, however, constructed of heat insulating material such as asbestos, so as to confine the generated heat to the resistance sec-

tions and their supporting block, and to confine the generated heat to upward flow against the objects placed over the base to be heated.

The stove may be of any suitable construction. The form shown in Fig. 1 accommodates only one heating unit, but it is obvious that any number of heating units can be applied to different stove constructions, and that heating units may also be applied in ovens or other heating compartments of the stove for baking, water heating, or other purposes.

By referring to Figs. 2 and 3 the supply circuit arrangement for the unit can be readily understood. A switch *A* is shown comprising two blades 33 and 34 connected with the main supply conductors *L*—*L'*, the blade 33 at its end having the arcuate extension 35. Contact buttons 36 and 37 and a contact plate 38 are provided for engagement with the switch blades. The contact buttons 36 connects with the conductor 39 leading to the screw 22 connected with the spring jaw 24, and button 37 connects with conductor 40, which leads to screw 23 connected with switch jaw 25, while the contact plate 38 connects with conductor 41 which leads to screw 27 connected with spring jaw 29. When the switch parts are in the position shown in Fig. 2 current will flow from the main conductor *L* through the switch blade 33, button 36, conductor 39, screw 22, spring jaw 24, contact pin 12, conductor plate 11 to the terminal screw of winding section *a*, then through resistance sections *a*, *c*, *e*, *g* and *i*, through conductor plates 15 and 16, then through resistance sections *j*, *h*, *f*, *d* and *b* to conductor strip 13, contact pin 14, spring jaw 25, screw 23, conductor 40, button 37, and switch blade 34 to line *L'*. The resistance sections are, therefore, all in series to offer the greatest amount of resistance and therefore to give a minimum degree of heat. If the switch is moved to the position shown in Fig. 2^a the switch blade 33 through its extension 35 remains in contact with the button 36, but the switch blade 34 leaves button 37 and engages with the contact plate 38, and the circuit will be as follows: from the main line *L*, switch blade 33, extension 35, button 36, conductor 39, screw 22, spring jaw 24, resistance sections *a*, *c*, *e*, *g* and *i*, conductor plate 15, contact pin 17, conductor 41, contact 38, and switch blade 34, to line *L'*. With this arrangement only one-half of the resistance sections are inserted and the resistance reduced one-half to give intermediate heating conditions. If the switch is now moved to the position shown in Fig. 2^b the switch blade 33 by its extension 35 will be in contact with both buttons 36 and 37, and switch blade 34 will remain in contact with the bar 38, and the circuit condi-

tions will be as follows: line L, switch blade 33, and buttons 36 and 37, the circuit now dividing, part of the current flowing through conductor 39 and resistance sections *a, c, e, g* and *i* to the contact pin 17, and the other part flowing through conductor 40 and through resistance sections *b, d, f, h* and *j* to the contact pin 17, the current then returning through conductor 41, contact 38 and switch blade 34 to line L'. With this arrangement there are two parallel circuits through the resistance sections, each including one-half of the resistance sections, and we have the maximum heating conditions. Thus, by setting the switch to various positions, minimum, intermediate or maximum heating conditions can be established. The switch mechanism can be of a construction as shown in Figs. 2, 2a and 2b, or in the form of a snap switch A (Fig. 1) or of any other suitable style, and is preferably mounted on the stove frame in any convenient position. Other combinations of the resistance sections and circuit could, of course, be provided or added, and the switch mechanism correspondingly modified to be actuated to select any circuit arrangement, depending upon the heating conditions desired.

In the form shown in Figs. 2 and 3, the wire sections lie in the open grooves and are, therefore, practically entirely exposed. In Fig. 6 I have shown a modified arrangement which involves the application of a filler *f* in the grooves to partly or wholly cover the resistance sections, and the filler is preferably of the same heat conducting material as that of the supporting block. In the modification shown in Fig. 7 no ridges or grooves are provided, the block being flat on both faces and the sections being molded or cast into the block preferably near the upper surface thereof, the heat from the sections being transmitted to the material of the block. In the modification in Fig. 8 the ridges and channels are provided, but the sections, instead of lying in the grooves, are molded or cast in the ridges near the apexes thereof.

In the heating mechanism of our invention, as described, the units are of simple and of inexpensive construction and produce the most efficient heat conditions with a minimum of weight and volume. Not only do the resistance sections become heated, but the entire supporting block for the sections takes on heat to relieve the sections, and this block, together with the sections, gives a maximum radiating surface. The supporting base for the unit, being of heat insulating material, will prevent loss of heat and will concentrate the heat against the objects to be heated. If a single resistance section burns out it can quickly be replaced by a new section, or the entire unit can be readily lifted from its base and replaced by

a new one. By means of the switching mechanism various circuit combinations are provided for the sections to produce the desired heating conditions.

We do not desire to be limited to the forms and arrangements which we have shown and described, as other modifications both in construction and arrangement are possible which would still come within the scope of our invention, and we therefore claim the following:

1. A heating unit for electrical stoves, comprising a supporting block formed of material of high heat conductivity, a plurality of individual resistance conductors on said block, terminals on said block for said conductors, and cross connectors for said terminals for adapting said conductors for connection in various combinations with a current supply circuit. 85

2. In combination, a supporting block of material having high heat conductivity, a plurality of individual heating coils arranged on said block, terminals on said block for each coil, cross connectors on said block and connecting various coils in electrical relation, a source of current, circuits for supplying current flow from said source to said coils, and a single switch mechanism for controlling said circuits to select 95 and connect heat coils in various combinations with said current source. 90

3. In electrical heating mechanism, the combination of a block or base formed of heat insulating material and having a 100 pocket, electrical terminals mounted in said pocket and adapted for connection with a current supply source, a supporting block of material possessing high heat conductivity, a plurality of individual heating conductors supported on said block, and terminals on said block for said heating conductors, said terminals being adapted for electrical engagement with the terminals in said pocket upon application of said block in said 105 pocket. 110

4. In combination, a stove top having a depression, a base block for said depression, said base block being of heat insulating material and having a pocket, a supporting 115 block fitting in said pocket, a plurality of individual resistance conductors on said supporting block, terminals on said block for said resistance conductors, and electrical terminals mounted in said pocket and adapted to be engaged by the terminals of said block upon application of the block in said pocket. 120

5. In electrical heating mechanism, the combination of a base formed of heat insulating material and having a pocket, electrical terminal sockets mounted in said pocket and adapted for connection with a current supply source, a supporting block of material possessing high heat conduc- 125 130

tivity, a plurality of individual heating conductors supported in parallel on said block, and terminal pins on said block for said heat conductors, said terminal pins being adapted for engagement with said terminal sockets in the pocket of said base upon application of said block in said pocket.

In witness hereof, we hereunto subscribe our names this 3rd day of June, A. D. 1910.

GEORGE A. HUGHES.
TREVOR M. CAVEN.
